UNITED STATES PATENT OFFICE.

EMIL W. SCHULTZ, OF WATERTOWN, WISCONSIN, ASSIGNOR OF ONE-FOURTH TO MAX H. GAEBLER, OF WATERTOWN, WISCONSIN.

EXTENSION-TABLE.

1,189,298.

Specification of Letters Patent.

Patented July 4, 1916.

Application filed November 5, 1914. Serial No. 870,327.

To all whom it may concern:

Be it known that I, EMIL W. SCHULTZ, a citizen of the United States, residing at Watertown, in the county of Jefferson and State of Wisconsin, have invented certain new and useful Improvements in Extension-Tables, of which the following is a specification, reference being had to the accompanying drawing, forming a part thereof.

10 This invention relates more particularly to extension tables having single central pedestals and equalizing devices whereby the end sections of the top are caused to move equally and simultaneously in opposite directions, enabling one person at either end of a table to open and close the same.

It also relates to slides of the class shown and described in United States Letters Patent No. 626,747, dated June 13, 1899.

20 The main objects of the invention are to prevent binding and sticking of the bars, especially when subjected to load or incorporated in tables of the kind above mentioned having equalizing devices and supported by single inseparable central pedestals, and generally to simplify and improve the construction and facilitate the operation of slides and tables of the class above mentioned.

30 It consists in the construction, arrangement and combination of parts as hereinafter particularly described and pointed out in the claims.

In the accompanying drawing like characters designate the same parts in the several figures.

Figure 1 is a vertical cross section on the line 1—1, Figs. 2 and 4, of two adjoining bars of a slide embodying the invention; 40 Fig. 2 is a side elevation of a portion of one of the bars as viewed from the left relative to Fig. 1; Fig. 3 is a longitudinal section on the line 3—3, Fig. 2; Fig. 4 is an inverted plan view on a reduced scale of an extension table showing the table closed and slide bars and equalizing devices as applied thereto, according to the invention, the pedestal being shown in section; and Fig. 5 is a similar view of one of the slides and associated parts 50 of the top section, extended.

In accordance with the invention an extension table having a single inseparable central supporting pedestal and equalizing devices is provided with two slides constructed and arranged as shown in Figs.

4 and 5. Each slide comprises three bars *a*, *a'*, formed in their adjoining sides, as shown in Figs. 1, 2 and 3, with longitudinal T-shaped or undercut grooves *b*, of well known construction. Each bar is provided 60 at or adjacent to one end with a block *c*, which is fitted and secured in the groove *b* and projects therefrom laterally into the contracted portion of the groove *b* in the adjoining bar. The block protrudes from the 65 bar in which it is fastened, a distance approximately equal to the depth of the contracted portion of the groove in the adjoining bar; and the projecting portion thereof is made somewhat narrower than the contracted portion of the groove which it enters 70 so as to clear the upper and lower sides thereof, as shown in Fig. 2.

A roller *d*, preferably of metal, is loosely fitted in an approximately circular recess *e*, 75 in the protruding portion of the block, and is pivoted or journaled on a screw or pin *f*. The recess *e* is of somewhat greater depth than the thickness of the roller *d*, and forms a seat for the convex face of a washer *g*, 80 which is clamped or secured to its seat by the screw or pin *f* passing through the block into the bar. The washer, which is of greater diameter than the roller *d*, and may be conveniently stamped as shown, from 85 sheet metal in concavo-convex form, serves not only by engagement with the undercut portions of the groove in which the roller travels to tie adjoining bars together and hold them in the proper working relation to 90 each other, but also to firmly support the outer end of the pivot screw or pin *f* next to its head and prevent it from being bent, or loosened and displaced by the weight to which the roller is subjected. The convex 95 face of the washer not only prevents it from gouging into and mutilating the overhanging sides of the groove with which it engages, causing it to work smoothly and freely therein, but also entering the recess *e*, in which it is seated, holds it firmly in place against vertical or lateral displacement. A common wood screw, as shown, is preferably used to secure the washer to the block *c* and the bar in which the block is inserted, 100 and to form the pivot of the roller, but a wire nail or cylindrical pin having a head at one end, might be used.

The middle bar *a'* of each slide is fastened to the cross piece *h* at the upper end of the 110

pedestal *i*, as shown in Figs. 1 and 2. The other two bars *a*, are fastened to the separable top sections *j*, and are provided with racks *k*, meshing with opposite sides of a pinion *l* pivoted centrally on the middle bar *a'*. Any movement of either top section *j* operates through the slide bars *a a'*, racks *k* and pinions *l* to produce a like movement of the other top section in the opposite direction.

10 The anti-friction rollers *d* and convex washers *g* connecting the bars of each slide with one another insure perfect freedom of movement of the bars *a* lengthwise of the stationary middle bars *a'*, thus enabling a single person without aid and without displacing the pedestal even if it is provided with casters and stands on a polished or smooth floor, to easily extend or close the table by grasping either top section and pulling it outward or pushing it inward. This freedom of movement of the slide bars not only facilitates the opening and closing of the table, but also prevents scratching or marring polished floors or rumpling carpets or rugs incident to the movement of the pedestal thereon.

Various changes in details of construction and arrangement of parts may be made 30 without departure from the principle and scope of the invention as defined in the following claims.

I claim:

1. In an extension table the combination 25 with slide bars having undercut grooves in their adjoining faces, of a block secured in the groove in one bar and projecting therefrom loosely into the contracted portion of

the groove in the other bar, a roller let into an approximately circular recess in the protruding portion of said block and projecting above and below the same, a washer seated in said recess over said roller and adapted to engage with and run in the groove of the adjoining bar, and a pin forming a pivot 45 for the roller and securing the washer to its seat in said block, the washer serving to firmly and centrally support the outer end of the pin and the roller from the block in which the washer is seated and held by the 50 pin.

2. In an extension table the combination with slide bars having undercut grooves in their adjoining faces, of a block secured in the groove of one bar and projecting therefrom loosely into the contracted portion of the groove in the other bar, a roller loosely fitting in an approximately circular recess in the protruding portion of the block and projecting above and below the same, a washer of greater diameter than the roller and having a convex face fitting into said recess, and a headed pin passing loosely through and forming a pivot for the roller and binding the washer to its seat on said block, the washer centrally and firmly supporting the outer headed end of the pin and the roller from the margin of the recess in which the washer is seated and held by the 65 pin.

In witness whereof I hereto affix my signature in presence of two witnesses.

EMIL W. SCHULTZ,

Witnesses:

GUSTAV BECHMANN,

WILLIAM KRUEGER.
